ABSTRACT

A zinc oxide compound nonlinear resistance overvoltage surge arrester disc is provided with a low temperature-curing ceramic antiflashover collar having relatively low coefficient of thermal expansion of about 4.5×10^{-6} . The cured ceramic comprises the reaction product of a dry mixture of 80% by weight of mullite refractory filler and 20% kaolin suspending clay, together with 5% to 15% of the weight of the dry mixture of a binder consisting of equal weights of monoaluminum phosphate and concentrated phosphoric acid.

Also disclosed is a method of application comprising the steps of applying the slurry to the perimeter of the disc and baking at a temperature below about 600° Celsius.
